UNITED STATES PATENT OFFICE

JOHN F. CAMERON, OF SEATTLE, WASHINGTON

WRENCH

Application filed May 7, 1932. Serial No. 609,930.

The present invention relates to a wrench of the slidable inner jaw type and has for its primary object to provide, in a manner as hereinafter set forth, a wrench of this character embodying novel construction, combination and arrangement of parts, through the medium of which adjustments of the inner jaw may be accomplished expeditiously and with a minimum of effort.

Other objects of the invention are to provide a wrench of the character described which will be simple in construction, strong, durable, efficient and reliable in use, compact, and which may be manufactured at low cost.

All of the foregoing and still further objects and advantages of the invention will become apparent from a study of the following specification, taken in connection with the accompanying drawings, wherein like characters of reference designate corresponding parts throughout the several views, and wherein:—

Figure 1 is a view in side elevation of a wrench constructed in accordance with the present invention.

Fig. 2 is a view in vertical section through the wrench.

Fig. 3 is a view in front elevation of the wrench.

Fig. 4 is a detail view in side elevation of the inner jaw.

Referring now to the drawings in detail, it will be seen that the embodiment of the invention which has been illustrated, comprises a shank 1 having inner end portions formed to provide a handle 2. Integral with the outer end of the shank 1 is a substantially right angular extension toothed stationary outer jaw 3. On its inner side and extending from the outer jaw 3 substantially to the handle 1, the shank 1 is provided with a recess 4 in which is mounted a rack bar 5.

The rack bar 5 is secured in position by suitable elements 6 which will permit the removal and replacement of the rack bar when the same becomes worn.

Mounted for sliding and rocking movement on the shank 1 and disposed in opposed relation to the stationary outer jaw 3 is an inner jaw 7 having a depending portion 8 pro-

vided with a longitudinal slot 9 at an intermediate point. Yokes 10 and 11 are rigidly secured to the slidable jaw 7 and slidably receive the shank 1 for mounting said jaw 7 thereon. The yoke 11 is of a length to maintain the lower end portion of the extension 8 comparatively close to the ratchet bar 5, while the yoke 10 is comparatively long to permit rocking movement of the jaw 7.

A dog 12 is pivotally mounted, as at 13, in the slot 9 for opposite engagement with the ratchet bar 5 while releasably securing the slidable inner jaw 7 in adjusted position. The tail 14 of the dog 12 projects over the upper portion of the extension 8. The dog 12 is yieldingly urged into engagement with the ratchet bar 5 by a coil spring 15 having one end engaged with the tail 14 and its other end engaged in a socket 16 provided therefor in the extension 8.

In use, when it is desired to adjust the jaw 7 towards the stationary jaw 3, it is only necessary to exert pressure in the proper direction. The dog 12 will ride over the teeth of the ratchet bar 5 to permit adjustment in this direction. When it is desired to adjust the jaw 7 away from the stationary jaw 3, this may be conveniently accomplished by engaging the index finger with the bight portion of the yoke 10 and actuating the dog 12 by exerting pressure on the tail 14 with the thumb to disengage said dog 12 from the ratchet bar 5 against the tension of the coiled spring 15. Of course, when the dog 12 is disengaged from the ratchet bar 15, the inner jaw 7 is free to be shifted. Should the dog 12 become worn, or the coil spring 15 weak, these elements may be conveniently removed and replaced with new ones. The jaw 7 and extension 8 are provided with a longitudinal groove or channel 17 in which the ratchet bar 5 is engaged. This is illustrated to advantage in Figs. 1 and 2 of the drawings.

The construction and arrangement herein illustrated and described is such that, when the wrench is applied to the work and pressure exerted on the handle 2 in one direction, the inner jaw 7 will be rocked from the position shown in Figs. 1 and 2 of the drawings inwardly with the obvious result that the

work will be tightly gripped between the jaws. When thus rocked, the jaw 7 fulcrums or pivots on the dog 12.

It is believed that the many advantages of a wrench constructed in accordance with the present invention will be readily understood, and although the preferred embodiment of the invention is as illustrated and described, it is to be understood that changes in the details of construction, and in the combination and arrangement of parts, may be resorted to, which will fall within the scope of the invention as claimed.

Having thus described my invention, what I claim as new is:—

A wrench comprising a shank, a handle on one end of the shank, a substantially right angularly extending stationary jaw on the other end of the shank, said shank having a recess in one side thereof, extending longitudinally therein, a ratchet bar secured in the

recess, said ratchet bar having its longitudinal edges inwardly offset from the corresponding edges of the shank, an inner jaw, an extension depending from the inner jaw adjacent the ratchet bar, said inner jaw and the extension having a longitudinal groove therein extending throughout the entire length of the jaw and the extension for the reception of the ratchet bar, the edges of the groove constituting guides abutting the sides of the ratchet bar to prevent transverse motion of the jaw, yokes carried by the inner jaw and the extension slidably engaging the shank for mounting the inner jaw thereon and a spring pressed pawl pivotally carried by the extension and cooperating with the ratchet bar for releasably securing the inner jaw in adjusted position.

In testimony whereof I affix my signature.

JOHN F. CAMERON.
